(57) **CLAIM**

The ornamental design for a sterilizing and charging box, as shown and described.

DESCRIPTION

FIG. 1 is a top, front, right perspective view of a sterilizing and charging box, shown in a closed configuration and in condition of use for clarity of disclosure;
FIG. 2 is a top, front, right perspective view of the sterilizing and charging box of FIG. 1;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, front, right perspective view of the sterilizing and charging box, shown in an open configuration for clarity of disclosure.

The broken lines in the figures depict portions of the sterilizing and charging box, that form no part of the claimed design.

1 Claim, 9 Drawing Sheets
